UNITED STATES PATENT OFFICE.

THEODOR BUCHHOLZ, OF BERLIN-ZEHLENDORF-WEST, GERMANY.

RAIL FASTENING.

Application filed May 27, 1926, Serial No. 112,135, and in Germany June 4, 1925.

The present invention relates to a rail fastening which enables the rail to be tightened so as to be absolutely secured and so as to provide a reliable joint between the rails. 5 This is effected by the joint and sole plate being provided with ribs of different height, of which the lower one lying inside of the rail serves for the reception of the clamping screws, while the high rib lying outside the 10 rail is provided with inwardly projecting parts, against which wedge-shaped pieces inserted between the rail and the higher rib abut, when the fixing bolts which extend through the rib, the wedge-shaped pieces 15 and the rail are tightened up.

In the accompanying drawing Figure 1 shows one constructional form of the invention with a high rib and a low rib, Figure 2 a portion of the low rib with the clamping 20 bolt for holding the bridging member in position and Figure 3 is a side elevation of a detail.

The sole plate *a* has a low rib *b* which is provided with a suitably formed recess for 25 the reception of the hammer-headed bolts *f*, which have heads with inclined sides. A high rib *c* is also provided, which has an inwardly projecting part *d*, against the inclined surface *t* of which a filling piece *e* 30 abuts. The filling piece *e* which is shown in side elevation in Fig. 3 is dished and on the fixing bolt *f* being tightened, is pressed by a collar *u* on the shank to the bolt with its 35 suitably formed inclined surfaces against the rail head and rail foot. The dished filling piece *e* is also so formed that, after being turned through 180°, the gauge can be adjusted by the suitably reduced or increased side walls being caused to abut against the 40 inclined surface *t*. In this way the filling piece, which may also be called a gauge-adjusting member, replaces two gauge adjusters of different sizes. The collar *u* and the corresponding abutment surface of the 45 filling piece *e* are preferably made wedge-shaped for producing a better clamping effect. On the other side of the rail a fish-plate *g* is provided, which, on the fixing bolt being tightened, is pressed against the 50 rail head and foot exactly similarly to the filling piece *e*.

For preventing the rail tilting about the point A towards the high rib *c* the rail foot lying close to the low rib *b* is held in position 55 by a clamping bridge piece *h*, the inner leg *h* of which is preferably so formed as to im-

press the outer edge of the rail foot. The projection *h* has the object of preventing the bridge piece from turning, when the hammer-headed bolt is tightened up. 60

The sole plate *a* is fixed to the sleeper by means of coach screws *k* in such a manner that the low rib *b* of the sole-plate will lie on the inner side of the rail so that the transverse thrusts on the rail head caused by the 65 flange of a wheel are taken up by the high rib *c* lying on the outside. In assembling the parts the nut *n* is first tightened which lies on the inner side of the rail, so that the fish-plate *g* and the filling piece *e* are pressed 70 firmly against the rail head and foot by the collar *u* provided on the bolt. Thereupon, by tightening the nut *n* the rail with the filling piece *e* and the fish-plate *g* are turned tightly into the space for the wedge, formed 75 by the high rib *c* and the plate *a*. Finally the bridging member *h* is tightened down, the inner leg *h* of which rests against the inner rail foot, whereby the rail is prevented from tilting about the point A. If the sole- 80 plate is to rest at the foot of the rail on two sleepers at a normal distance apart, it is made so strong that it alone can take up the thrust of the wheels. For increasing the moment of inertia the outer rib *c* can be 85 enlarged towards the top or raised. By this means the neutral zone is placed in the centre of the cross-section.

Figure 2 shows the low rib *b* with the inserted hammer headed bolt *f*. The rib 90 *b* is provided above the sole-plate with an upwardly tapering recess for receiving the hammer-headed bolt, so that good abutment surfaces are formed for the correspondingly formed hammer head, whilst the rib is 95 kept as low as possible.

What I claim is:

1. A rail joint and sole-plate comprising two ribs of different height, a low rib lying inside the rail and a high rib lying outside 100 the rail, a clamping bridge piece bridging over the low rib, a bolt for clamping the bridge piece to the low rib, an inwardly projecting piece on the high rib, a wedge-shaped piece capable of being placed between the 105 high rib and the rail and of resting against the said projecting piece and a bolt extending through the wedge-shaped piece and the rail for tightening the rail and the wedge-shaped piece against the high rib, as and for 110 the purpose set forth.

2. A rail joint and sole-plate comprising

- two ribs of different height, a low rib lying inside the rail and a high rib lying outside the rail, a clamping bridge piece bridging over the low rib, a bolt for clamping the bridge piece to the low rib, an inwardly projecting piece on the high rib, an asymmetrical wedge-shaped piece capable of being placed between the high rib and the rail and of resting against the said projecting piece 5
- 10 and a bolt extending through the wedge-shaped piece and the rail for tightening the rail and the wedge-shaped piece against the high rib, as and for the purpose set forth.
3. A rail joint and sole-plate comprising 15 two ribs of different height, a low rib lying inside the rail and a high rib lying outside the rail, a clamping bridge piece bridging over the low rib, a bolt for clamping the bridge piece to the low rib, an inwardly projecting piece on the high rib, a wedge-shaped piece capable of being placed between the high rib and the rail, an inclined surface on the inside of the high rib, an inclined surface on the side of the wedge-shaped member, capable of resting against the inclined surface of the high rib, the wedge-shaped member being capable of resting against the head and foot of the rail, and a bolt extending through the wedge-shaped piece and the 20 rail for tightening the rail and the wedge-shaped piece against the high rib, as and for the purpose set forth.
- 25 30 4. A rail joint and sole-plate comprising two ribs of different height, a low rib lying inside the rail and a high rib lying outside the rail, a clamping bridge piece bridging over the low rib, a bolt for clamping the bridge piece to the low rib, an inwardly projecting piece on the high rib, a wedge-shaped gauge adjusting member of rectangular cross-section capable of being placed between the high rib and the rail and of being turned for altering the gauge of the rails, and a bolt extending through the wedge-shaped piece and the rail for tightening the rail and the wedge-shaped piece against the high rib, as and for the purpose set forth.
5. A rail joint and sole-plate comprising 45 two ribs of different height, a low rib lying inside the rail and a high rib lying outside the rail, a clamping bridge piece bridging over the low rib, an upwardly tapering recess in the low rib, a bolt with a tapering hammer head capable of engaging in the said recess for clamping the bridge piece to the low rib, an inwardly projecting piece on the high rib, a wedge-shaped piece capable of being placed between the high rib and the rail and of resting against the said projecting piece and a bolt extending through the wedge-shaped piece and the rail for tightening the rail and the wedge-shaped piece against the high rib, as and for the purpose set forth.
- 50 55 60 In testimony whereof I have signed my name to this specification.

THEODOR BUCHHOLZ.
